UNITED STATES PATENT OFFICE

GEORGE P. CRAVEN, OF FRANKLINVILLE, NORTH CAROLINA

FOLDABLE HEAD SLAT

Application filed April 6, 1931. Serial No. 528,201.

This invention aims to provide novel means whereby a head rest for a barber's chair, a surgeon's chair, a dentist's chair, or a chair of any other kind, can be turned down readily, into an out of the way position, when not in use, the head rest, nevertheless, being rigidly supported when it is in operative position.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawing:

Figure 1 shows in rear elevation, a portion of a chair whereon the device forming the subject matter of this application, has been mounted;

Figure 2 is a vertical section;

Figure 3 is an elevation of the head rest support as it will appear when the head rest is in use;

Figure 4 is a longitudinal section of the head rest support, as it will appear when the head rest is not in use.

The device forming the subject matter of this application may be used upon chairs of many different kinds, but, in the drawing, there is shown a chair back 1 having an internal, vertical guide 2. The edge of the chair back 1 may carry a metal binding piece 3, which in cross section, is an angle member, the binding piece having a depending arm 4 which extends downwardly on the chair back. In the upper portion of the binding piece 3 there is a hole 5 in vertical alignment with the guide 2. A holding device, such as a spring-pressed latch 6, operates in the arm 4 and in the chair back 1, and is adapted to cooperate with the guide 2.

The numeral 7 designates a head rest sup-

port made out of links, each of which is fashioned from rigid metal. The lower link of the head rest support 7 is designated by the numeral 8 and is provided at its upper end with hinge knuckles 9. An intermediate link 10 is shown, and has a depending lug 11, located between the hinge knuckles 9. The intermediate link 10 has an upstanding lug 12 received between hinge knuckles 15 on the lower end of an upper link 14. A hinge pin 16 extends through the lug 12 and the hinge knuckles 15. A hinge pin 17 extends through the lug 11 and the hinge knuckles 9.

The construction is such that the head rest support 7 can be folded over from the position of Figure 3 to the position of Figure 4, but the head rest support has no flexibility laterally, that is in the direction of the arrows A, in Figure 3. The head rest 18 may be of any desired construction and is secured at 19 to the upper end of the upper link 14 of the head rest support 7. The upper link 14 of head rest support 7 is provided on its rear surface with a plurality of seats 20, arranged in longitudinal line. On the inner surface of the lower link 8, near to the upper end of the said link, there is a seat 21. The seats 20 and 21 are adapted to cooperate with the inner end of the latch 6.

When it is desired to maintain the head rest 18 in condition to use, the support 7 is slid downwardly in the guide 2 far enough, so that the hinge at 16-15-12 is within the guide. Then, the link 14 will extend upwardly, and will have its lower end mounted in the guide 2, so that the head rest 18 cannot swing backwardly or forwardly, or sideways. A vertical adjustment may be effected by sliding the head rest support 7 upwardly or downwardly, and the support is held in any position to which it may have been adjusted vertically, by engaging the latch 6 in any one of the seats 20-21. When the occasion for the use of the head rest 18 has passed, the latch 6 is retracted, and the head rest support 7 is slid upwardly into the position of Figure 2. The intermediate link 10 is folded backwardly and the upper link 14 is folded downwardly, the head rest 18, thus,

being disposed in an out of the way position. The length of the intermediate link 10 is somewhat greater than the horizontal distance between the guide 2 and the rear surface 5 of the arm 4, and, consequently, when the upper link 14 is swung downwardly into the position of Figure 1, it can hang close to the rear surface of the chair back 1, the head rest 18 being positioned accordingly.

- 10 The binding 3, which is mounted on the upper, rear corner of the back 1, includes a horizontal flange covering the upper end of the guide 2, and a vertical depending flange overlapped on the rear surface of the back. 15 The hole 5 in the horizontal flange is in alignment with the guide 2. The links 8, 10 and 14 are slideable through the hole 5 of the horizontal flange, into the guide 2. The horizontal flange directs the links 8, 10 and 14 into 20 the guide 2. Both flanges of the binding 3 are interposed between the links and the outside of the back, to prevent the links from wearing the upper portion of the back, as the links are slid up and down in the guide, and 25 as the support is flexed to hang dependent behind the back.

The device is further characterized by the fact that, as shown in Figure 2, the latch 6 projects rearwardly beyond the vertical flange of the binding 3, and engages the link 14 which carries the head rest 18, when said link is folded downwardly along the back. The latch 6 then spaces the said link 14 and the head rest 18, from wearing contact with 35 the back, as shown in Figure 2, and the link 14 holds the latch 6 engaged with the link 8.

Having thus described the invention, what is claimed is:

- 40 A chair for the use of barbers, surgeons, dentists, and others of similar calling, having a back which is provided with an internal, substantially-vertical guide spaced from the front and rear surfaces of the back, a binding mounted on the upper, rear corner of the 45 back and including a horizontal flange covering the upper end of the guide, and a vertical, depending flange overlapped on the rear surface of the back, the horizontal flange having a hole in vertical alignment with the 50 guide, a support comprising a plurality of links pivotally joined together, end to end, and slideable through the hole of the horizontal flange, into the guide, the horizontal flange directing the links into the guide, both 55 flanges being interposed between the links and the outside of the back, to prevent the links from wearing the upper portion of the back, as the links are slid up and down in the 60 guide, and as the support is flexed to hang dependent behind the back; a head rest on the outer end of the support and carried by one of the links, and a latch guided in the vertical flange and slideable through a portion of the back, into and out of engagement with divers 65 of the links, the latch projecting rearwardly

beyond the vertical flange, and engaging the link that carries the head rest, when said link is folded downwardly along the back, the latch then spacing said link and the head rest from wearing contact with the back, and said link holding the latch engaged with another of the links.

In testimony that I claim the foregoing as my own, I have hereto affixed my signature.
